UNITED STATES PATENT OFFICE.

MYRON S. TELLER, OF KINGSTON, NEW YORK.

DESIGN FOR A MEMORIAL TABLET.

SPECIFICATION forming part of Design No. 35,405, dated December 3, 1901.

Application filed November 6, 1901. Serial No. 81,266. Term of patent 31 years.

To all whom it may concern:

Be it known that I, MYRON S. TELLER, a citizen of the United States, and a resident of Kingston, in the county of Ulster and State 5 of New York, have invented and produced a new and original Design for a Memorial Tablet, of which the following is a full, clear, and exact description.

Reference is to be had to the accompanying 10 drawings, forming a part of this specification, in which similar characters of reference indicate corresponding parts in both the figures.

Figure 1 is a front elevation of a memorial tablet, showing my design; and Fig. 2 is a vertical section thereof.

My design for a memorial tablet comprises the side pilasters 1, arranged on a back plate 2 and extended upward from a base-plate 3, underneath the ends of which are brackets 4. 20 These brackets are connected one with the other by a plate 5, having scrolls on its lower edge extended laterally from a rosette 6. Between the fluted pilasters is a panel 7, and at the upper end of the pilasters is an ornamental frieze 8, in which garlands of flowers are 25 indicated. The caps 9 on the pilasters are

provided with rosettes, and supported on these pilaster-caps is the top piece or cap, having its opposite edges made in the form of scrolls 10, which are curved upward and 30 inward and spaced apart at the top, and these upper ends are formed with rosettes 11. This upper cap projects forward of the pilasters, and the scrolls 10 are connected by a plate 12, on which are represented a shield and an 35 eagle. Rearward of the shield and eagle and supported on the back plate 2 is an urn 13, on the body of which are festoons of flowers, and on the top is the representation of a torch or flame.

Having thus described my invention, I 40 claim as new and desire to secure by Letters Patent—

The design for a memorial tablet as herein shown and described.

In testimony whereof I have signed my 45 name to this specification in the presence of two subscribing witnesses.

MYRON S. TELLER.
